HORACE L. WORDEN, OF PHOENIX, ARIZONA.

HYDRAULIC SPEED-CHANGING AND REVERSING MECHANISM.

1,147,586.

Specification of Letters Patent. Patented July 20, 1915.

Application filed August 13, 1913. Serial No. 784,570.

To all whom it may concern:

Be it known that I, HORACE L. WORDEN, a citizen of the United States, residing at Phoenix, in the county of Maricopa and State of Arizona, have invented new and useful Improvements in Hydraulic Speed-Changing and Reversing Mechanism, of which the following is a specification.

This invention relates to hydraulic speed changing and reversing mechanism, the object in view being to produce changeable speed and reversing transmission mechanism designed to be introduced between a drive and driven shaft in various types of machinery whereby, with the aid of manual control, any desired speed may be imparted to the driven shaft and the direction of rotation of said driven shaft reversed and said shaft driven at any desired rate of speed in either direction. The mechanism also provides for applying braking power to the driven shaft and also entirely stopping said driven shaft according to the desire of the operator.

A further object of the invention is to produce changeable speed and reversing mechanism of the character above referred to without the use of any gears or pulleys as said terms are generally understood and also to secure the desired braking action without the use of the usual brake bands, straps, shoes and other ordinary friction devices.

With the above and other objects in view, the invention consists in the construction, combination and arrangement of parts, as will hereinafter be more fully described, illustrated and claimed.

In the accompanying drawings: Figure 1 is a longitudinal section through the entire mechanism taken on the line 5—6 of Figs. 2 and 3. Fig. 2 is also a longitudinal section through the mechanism taken on the line 1—2 of Fig. 1. Fig. 3 is a cross section on the line 3—4 of Fig. 1. Fig. 4 is an end elevation of one of the members of either the pump or motor showing the means for packing the working faces thereof. Fig. 5 is a detail edge view of one of the wings thereof. Fig. 6 is a longitudinal section through one of said wings. Fig. 7 is a detail view of one of the packing sections.

Referring primarily to Figs. 1, 2 and 3 which illustrate the invention in compact form, A designates a hydraulic pump and B a motor.

In the preferred and simplest embodiment of this invention, the two members of the pump are constructed and relatively arranged for coöperation as illustrated in the cross section Fig. 3 and it may be noted at this point that the two members of the motor B are of exactly the same construction so that the cross section Fig. 3 would apply to the motor B as well as to the pump A, it being therefore considered unnecessary to separately illustrate both portions of the mechanism referred to in cross section.

As shown in Figs. 1 and 3, the shaft C of one member of the pump is stationary and round in cross section and is surrounded by an annular series of anti-friction rollers 1 which are contained within the bore of the pump member as clearly shown in Fig. 3 thereby permitting said pump member to revolve with a minimum amount of friction. The other pump member indicated at A' is of the same size and outer contour as the member A but is shown as mounted on the squared portion 2 of a driving shaft F which may derive its motion from any suitable engine.

The rotary pump members A and A' are provided with a corresponding number of wings 3 extending longitudinally thereof and coöperating with each other as clearly shown in Fig. 3, both of said members being mounted rotatably in a pump casing 4 having an inlet passage 5 which is controlled by a manually operable valve R. This valve R is designed to be opened to a greater or less extent by hand so as to regulate the amount of liquid which may be drawn by suction into the pump casing 4 by the action of the members A and A' of the pump. In this way the speed of the driven shaft hereinafter referred to may be regulated.

The members B and B' are the exact counterparts of the pump members A and A' and are mounted within a casing 6 corresponding with the pump casing 4. The member B' is mounted on the squared portion of the driven shaft E.

7 and 8 designate stuffing box glands which are fastened to the opposite heads 9 and 10 of the frame or casing of the machine by means of bolts 11 containing nuts 12 by means of which the glands may be adjusted. The heads 10 are secured to the pump and motor casings 4 and 6 by means of screws or bolts 13.

Interposed between the pump and motor

casings is a valve casing 14 containing an inlet passage H from the pump casing, said passage H being formed about centrally of the casing 14 with a T-extension 15 leading in opposite directions to two valve chambers 5 in which are arranged valves K and L having ports extending through the same as best illustrated in Fig. 2. From the valve K a passage M leads into the motor casing at 10 one side of the members B and B' while another passage N leads from the valve L into the casing 6 at the opposite side of the members B and B'. These valves K and L are provided with stems G which extend outwardly and project beyond the casing as indicated in Fig. 1, said valve stems passing through stuffing boxes 16. The stems G are connected together by any convenient means so that they may be simultaneously operated. 15 20 Outlet or return passages O and P extending through opposite sides of the casing 14 are controlled by the valves K and L from which the liquid supply leads back to a suitable reservoir hereinafter referred to enabling the liquid to be used over and over again. The valve casing 14 is fastened to the pump and motor casings by means of screws 17 or their equivalent.

It will now be understood that the rotary 30 pump is actuated by the driving shaft F, drawing the oil or other liquid through the valve R, the latter being manipulated at the will of the operator to increase or diminish the flow of liquid. The liquid is forced 35 through the valve K and passage M into the motor chamber, driving said motor in one direction and imparting a corresponding movement to the driven shaft E. The liquid then returns through the passage N, the 40 valve L and passage P back to the reservoir where it is available for further use. As above indicated the valves K and L are linked together so that they may both be simultaneously shifted or turned by the operator to reverse conditions, or in other 45 words, to reverse the direction of movement of the liquid through the motor chamber, thus effecting a reversal of the shaft E; thus the liquid passes from the passage H 50 through the valve L and passage N into the motor chamber and returns therefrom through the passage M, valve K and outlet passage O back to the reservoir.

If the operator wishes to stop the driven 55 shaft E, the valves K and L are turned so as to close the passages M and N and leave free the passages O and P, which both communicate with the reservoir. Should the operator desire to change the speed of the 60 motor B and consequently the driven shaft E, this is accomplished by adjusting the valve R which controls the amount of liquid supply to the rotary pump. To utilize the mechanism as a brake for the shaft E, the 65 valves K and L are partially closed accord-

ing to the amount of braking action desired, thereby equalizing the pressure of the liquid on both sides of the members B and B'.

In order to obtain a liquid-tight fit between the wings of the members A and A' 70 of the pump and also the members B and B' of the motor, the construction illustrated in Figs. 4 to 7 inclusive is resorted to. In said figures 18 designates one of the members of either the pump or the motor and 19 the 75 wings thereof. Each of said wings is provided in its opposite end with grooves 20 in which are placed metal packing plates or strips 21 held in place by screws or their equivalent 22. The outer extremities of the 80 plates 21 are cut away or recessed as shown at 23 to receive the opposite extremities of peripherally arranged metal packing strips 24 one of which is shown in detail in Fig. 7, the extremities of said strip being notched 85 as shown at 25 to interlock with the notched extremities of the end strips 21. The strip 24 is also formed with slots 26 extending transversely thereof and receiving retaining pins 27 which pass transversely through the 90 outer portion of each wing 19, the slots 26 admitting of the necessary radial movement of the strip 24 to provide for a close contact between each and every wing of the member 18 and the adjacent co-operating member, as 95 well as the inner wall of the casing 4 or 6, as the case may be, in which the member 18 works.

It will therefore be apparent from the foregoing description that the pump and 100 motor may either be closely coupled or remotely located, in the latter case being connected together by suitable piping.

While I have only described a few applications of the changeable speed and reversing mechanism of this invention it will also be perfectly obvious that the mechanism referred to may be applied to various other kinds of machinery and vehicles such as water craft, wind mills, individual shop machinery drives, such as lathes, drill presses, grinders, milling machines, planers, shapers, printing presses, ruling machines, paper cutters and other machines too numerous to mention. 115

What I claim is:

Hydraulic transmission mechanism comprising a pump casing, a valve casing, and a motor casing, all arranged in tandem relation to each other with the valve casing 120 interposed between the pump and motor casings and forming the inside heads of the last named casings, a driving shaft entering the pump casing, a pump actuated by said shaft, a driven shaft in longitudinal alignment 125 with the driving shaft entering the motor casing, a motor in the last named casing actuating said driven shaft, the valve casing embodying a three way passage one branch of which enters the pump casing and the 130

other branches entering the motor casing, and other passages intersecting the last named branches and both communicating with a common liquid supply, and a pair of valves controlling said branches and adjustable to open communication between the pump casing and either of said last named branches, regulate the flow of liquid, and

reverse the motor, and also cut off the flow of liquid to the motor. 10

In testimony whereof I affix my signature in presence of two witnesses.

HORACE L. WORDEN.
